WILLIAM J. BARGEN, OF MISSOULA, MONTANA.

ARTICLE OF FURNITURE.

Application filed July 1, 1926. Serial No. 119,870.

This invention relates to furniture, more particularly school room furniture, such as a combined seat and study support, but it is to be understood that an article of furniture, 5 in accordance with this invention, can be employed and used in any connection for which it is found applicable, and the invention has for its primary object to provide, in a manner as hereinafter set forth, an article of furniture including a seat having arranged forwardly thereof a study support, the latter being in the form of a book box or desk body or a tablet arm, and a pedestal common to the seat and support, acting as 10 the sole supporting element for these latter, and including inherent means for anchoring the article of furniture in a stationary position when in use, but said means further permitting of the shifting of the article of furniture when desired, or using it without anchoring to the floor.

A further object of the invention is to provide an article of furniture for use primarily in connection with school rooms including a 25 seat carrying a study support, adjustable relative to the seat, to afford maximum amount of comfort with respect to the disposition of the scholar's or pupil's arms, feet and legs, and further including a pedestal common to the seat and study support and 30 acting as the sole supporting element for these latter.

A further object of the invention is to provide in a manner as hereinafter set forth, an 35 article of furniture primarily designed for use in connection with school rooms and including an adjustable seat carrying a study support adjustable relative to the seat and whereby the seat adjustment, as well as the 40 study support adjustment will provide for the article of furniture to be used by pupils or scholars of varying heights and weights and further to afford maximum amount of comfort to the pupil or scholar when the 45 article of furniture is used.

A further object of the invention is to provide, in a manner as hereinafter set forth, an article of furniture for use in connection with school rooms and consisting of a movable chair desk with a book box under a writing top.

A further object of the invention is to provide, in a manner as hereinafter set forth, a 50 movable chair desk having a book box under the writing top and with the book box car-

ried by and adjustable relatively to the chair and further with a single pedestal providing the sole supporting means for the chair, writing top and book box.

Further objects of the invention are to 60 provide, in a manner as hereinafter set forth, an article of furniture for the purpose referred to and which is simple in its construction and arrangement, strong, durable, compact, readily adjustable, convenient in its 65 use, including inherent means for anchoring the same stationary, capable of being readily shifted to any desired point, and comparatively inexpensive to manufacture.

With the foregoing and other objects in 70 view, the invention consists of the novel construction, combination and arrangement of parts as hereinafter more specifically described, and illustrated in the accompanying drawings wherein are shown embodiments of 75 the invention, but it is to be understood that changes, variations and modifications can be resorted to which fall within the scope of the claims hereunto appended.

In the drawings wherein like reference 80 characters denote corresponding parts throughout the several views:

Figure 1 is a side elevation of an article of furniture in accordance with this invention.

85

Figure 2 is a top plan view thereof.

Figure 3 is a vertical sectional view thereof.

Figure 4 is a section on line 4—4, Figure 1.

90

Figure 5 is a section on line 5—5, Figure 1.

Figure 6 is an elevation of one of the sides of the chair.

Figure 7 is a top plan view of the structure shown in Figure 6.

95

Figure 8 is a rear elevation of the chair back, partly in section.

Figure 9 is a top plan view of the pedestal.

Figure 10 is a fragmentary view in section, of the chair or seat bottom.

100

Figure 11 is a vertical sectional view of the desk body or book box.

Figure 12 is a section on line 12—12 Figure 11.

Figure 13 is a section on line 13—13 Figure 11.

Figure 14 is a view of a connecting rod forming an element of the desk body or book box.

Figure 15 is an elevation of the adjustable supporting plate for the desk body or book box.

Figure 16 is a side elevation of an article of furniture in accordance with this invention set up with a tablet arm in lieu of a desk body or book box.

Figure 17 is a top plan view of Figure 16.

Figure 18 is a section on line 18-18, Figure 16.

Figure 19 is a detail, in sectional plan, of the side arm rear support for the tablet arm.

Figure 20 is a top plan view of the front support for the tablet arm.

Figure 21 is a detail.

Referring to the drawings in detail 1 denotes a pedestal provided with an enlarged base 2, preferably of polygonal contour. The base 2 is of the necessary weight and size to provide inherent means for anchoring the pedestal stationary, under such conditions overcoming the necessity of employing separate hold fast devices which extend through the base, for fixedly securing the same from movement. The weight of the base 2 however will not prevent of shifting the pedestal when desired. The weight of the base, as well as its size, provides for the use of the entire desk as a movable chair desk without fastening to the floor and prevents any possibility of the accidental tipping over of the chair desk. The pedestal is hollow and carries suitable means, as indicated at 3 for fixedly securing a vertically adjustable stem or standard 4 in position. The standard 4 is carried by the chair or seat, to be presently referred to, and provides means for elevating and lowering the seat or chair to the desired point and after the chair 4 has been adjusted it is fixedly secured within the pedestal 1 by the means 3.

The seat or chair, which will be herein-after referred to as a chair, with reference to Figures 1 to 8, comprises a rectangular bottom 5 formed in its upper face with a concave depression 6. The depression 6 extends to the rear edge of the seat bottom 5 but terminates adjacent the side edges and front edge of said seat bottom. The chair 50 is constructed with but one side arm, termed a side plate and which permits the scholar or pupil to enter the chair from one side thereof or at the front. The side plate which is referred to generally by the reference character 8 is formed of a rectangular body portion 9 of substantial width and length and provided with a pair of diagonally disposed openings 10. Formed integral with the outer face of the body portion 9 is a pair of spaced diagonally disposed webs 11, 12 which are arranged in parallelism. The web 11 has its lower end terminate at the rear end of the body portion 9 intermediate the top and bottom of the latter and the web 9 has its upper end curved rearwardly as at 27 is an inwardly extending flange 28, clear-

13 and positioned at the top edge of the body portion 9. The curved upper end of the web 11 is positioned intermediate the ends of the top edge of the body portion 9. The web 12 extends from the bottom edge of the body portion 9, at a point intermediate the ends of said bottom edge, and has its upper end formed with a forwardly curved portion 14 which terminates at the front edge of the body portion 9, intermediate the top and bottom edges of the latter. The webs 11 and 12 constitute guides and that portion of the body portion 9 arranged between the webs 11 and 12 forms what may be termed a guide

passage in connection with said webs. The curved upper end 13 of the web 11 terminates in a rearwardly directed rib 15 which extends to the rear end of the body portion 9 and is flush with the top of the latter. Formed integral with the body portion 9, at the bottom thereof, is an inwardly extending, right angularly disposed flange 16. Projecting inwardly from the flange 16 is a pair of spaced arms 17, 18 and with the former arranged in advance of the latter and positioned at the forward end of the body portion 9. The lower end of the web 12 merges into a vertically disposed depending flange 20 which is co-extensive with the forward side of the arm 18 and depends from the latter. The upper end of the web 12 terminates into a depending flange 21 positioned at the forward edge of the body portion 9 and which extends downwardly with respect to the latter and furthermore is co-extensive with the forward side of the arm 17 and depends from the latter. Formed integral with the outer face of the body portion 19, at the lower part thereof and spaced from the flange 21 is a vertically disposed flange 22 which is co-extensive with the inner side of the arm 17 and depends from the latter. The arrangement of the flanges 20, 21 and 22 with respect to the arms 17 and 18 are clearly shown in Figure 4. The arms 17 and 18 have their outer end portions integral with the lower face of the flange 16, see Figure 4. The body portion 9 projects rearwardly from the chair bottom 5, see Figure 4, and the lower face of the chair bottom 5 is rabbeted as at 23 for the reception of the flange 16. Hold fast devices 24 extend through the arm 18 for securing the latter to the chair bottom 5. Hold fast devices 25 extend through the arm 17 for securing the latter to the chair bottom 5. The inner lower corner of the body portion 9 is extended downwardly as at 26 and depends below the flange 16. The body portion 9, at its upper corner, is formed with a vertically disposed and rearwardly inclined tapering extension 27. Formed integral with the inner face of the body portion 9 and co-extensive with the extension 27 is an inwardly extending flange 28, clear-

80

110

115

120

125

130

ly shown in dotted lines in Figure 6. The flange 28 at its lower end merges into the rear end of the flange 16 and said flange 28 is positioned forwardly with respect to the 5 rear end of the body portion 9. The flange 28 is curved in the direction of its length and for a part of its length is positioned forwardly with respect to the rear edge of the extension 27, and for another portion 10 of its length is flush with the rear edge of said extension. The lower part of the extension 27 and upper part of the body portion 9 forwardly with respect to the flange 28 is slotted and the slotted portion of the 15 extension 27 merges into the slotted portion of the body portion 9 and which provides a vertically disposed slot indicated at 29 and enlarged intermediate its ends as at 30. The rear part of the body portion 9, in connection with the extension 27 and flange 28 provides a support for the chair back to be 20 presently referred to.

Secured to that side of the chair bottom 5 opposite the side to which the side plate 8 is secured, is a chair back support consisting of a horizontally disposed portion 31 and an upwardly extending and rearwardly curved portion 32. The portion 31 is angle shape in cross section and the horizontal 30 leg thereof is mounted in a rabbet 33 formed in the lower face of the chair bottom 5. Hold fast devices 34 are employed for securing the lower portion 31 of the chair back support to the chair bottom 5. The upward- 35 ly extending portion 32 is of angle shaped contour and formed with a lengthwise slot 35 which opposes the slot 29.

The chair back, as shown in Figure 8, includes an upper fixed back member 36, a lower fixed back member 37, and a vertically adjustable intermediate back member 38. The member 36 is fixedly secured to the back support by the hold fast devices 39 and the member 37 is fixedly secured to the back support by the hold fast devices 40. The member 38 is adjustably connected to the back supports, by adjusting devices 41 arranged in openings 42 and passages 43 formed in the member 38. The openings 43 are of 45 circular contour and are positioned adjacent the ends of the member 38 and the passages 43 lead to the openings 42 and open at the end edges of the member 38. The adjusting devices each consists of a headed bolt 44 50 extending through a passage 43 and carrying on its inner end an adjusting nut 45 arranged in the opening 42. The bolts 44 extend through the slots 29 and 35. The slot 35 is provided with an enlargement in the 55 same manner as the slot 29 and the enlarged portion of the slot permits of the mounting of the headed bolt in position. The slots 29 and 35 are of arcuate contour and are of a sufficient length to provide for the shifting 60 of the member 38 to the desired extent so

that the back of the scholar or pupil will be comfortably supported. The member 38 is of arcuate contour in vertical section, see Figure 3, and provides for what may be termed a hump. The member 36 projects 70 above the back support and the member 37 is positioned rearwardly with respect to the chair bottom 5.

Positioned against the lower face of the chair bottom 5 is a casting consisting of a 75 plate 46, formed with a pair of arms 47 at one end thereof and further provided with a pocket 48. The plate 46 is set up with a continuous depending flange 49 which is not only co-extensive therewith but also with 80 the arms 47. The arms 47 abut against the arms 17 and 18 and are secured therewith by one of the hold fast devices 24 and one of the hold fast devices 25. The plate 46 is secured to the chair bottom 5 by hold fast 85 devices 50. The arms 47 further act as a means for maintaining the arms 17 and 18 against the chair bottom 5. The standard 4 at its top is provided with a head piece 51, having reinforcing ribs on the lower face 90 thereof and said head piece 51 corresponds in contour to the shape of the pocket 48 and seats therein. The head piece 51 is fixedly secured to the plate 46, by the hold fast devices 52. The casting, of which the plate 46 95 is a part, has its top inclining downwardly from front to rear, see Figure 3, for the purpose of maintaining the chair bottom 5 at a slight downward inclination and with the inclination towards the rear of the chair 100 bottom. The pocket 48 however is not disposed at an inclination but squared whereby the standard 4 will not extend at an inclination, but will be perpendicular. See Figures 3 and 10. By inclining or tilting the 105 chair bottom 5 rearwardly it provides for supporting the pupil or scholar in the desired position and so that the pupil or scholar will not slide or readily slide off the front of the chair bottom 5. Owing to the manner in which the chair bottom 5 is secured to the standard 4, said chair bottom 5 110 is permanently maintained at a rearward inclination.

Adjustably connected to the side plate 8 is 115 an adjustable support for the desk or book box and which couples the latter with the chair so that the desk body or book box is supported from the chair. The adjustable support is in the form of an angle shaped plate and so formed that on its upward movement relative to the plate 8 will shift the book box or desk body upwardly and forwardly and when the support moves downwardly it will shift the desk body or book box towards the chair at the same time lowering it. The support, which is termed 120 a carrier is referred to generally by the reference character 53, and is best shown in Figures 1 and 15, and it further forms one 125 130

- of the side walls of the desk body or book box. The carrier 53 consists of a horizontally disposed portion 54 and an angularly disposed portion 55 which depends from and extends rearwardly at an inclination with respect to the portion 54. The portion 54 of the carrier 53 forms one of the side walls of the desk body or book box and is provided with an inwardly extending flange 56
 10 at its bottom, an inwardly extending flange 57 at its top, and an inwardly extending flange 58 at forward end. The function of the flanges 56, 57, 58 will be presently referred to. Preferably the flange 57 is of greater width than the flange 56, see Figure 13. The portion 55 is provided on its outer face with a countersunk portion 56' and with the wall of the latter indicated at 57'. The countersunk portion or recess 56' is substantially co-extensive with respect to the length of the portion 55 of the carrier. The portion 55 of the carrier is furthermore formed with a pair of forwardly inclined slots 58, 59, which are arranged in parallelism and the slot 58 is of greater length than the slot 59. The slots 58 and 59 are surrounded by a continuous flange 60 which corresponds in contour to the shape of the slot. The angularly disposed portion 55 of the carrier is positioned between the webs 11 and 12 of the plate 8 or rather positioned in the guide passage formed by the body portion 9 in connection with the webs 11 and 12. The angularly disposed portion 55 of the carrier 30 is slidably connected to the plate 8, by a pair of bolts 61 which extend through the slots 58 and 59 and also through openings 62 formed in the body portion 9 of the plate 8. See Figures 1 and 6 in connection with the foregoing. The body portion 9 of the plate 8 has its inner face formed with bosses 63 which surround the openings 62 and the walls of said opening 62 are threaded for engagement by the hold fast devices 61, see 40 Figure 5. Washers 64 are interposed between the heads of the hold fast devices and the flanges 60, see Figure 5. The hold fast devices 61 provide means for fixedly securing the carrier 53 in adjusted position. The slots 58 and 59 are of the necessary length to provide for the forward and upward and rearward and downward adjustment of the carrier 53 with respect to the chair or rather side plate 8 of the chair. The top of the portion 55 of the carrier 53 forms a continuation of the flange 57 of the portion 54 of the carrier and the upper corner of the portion 55 is extended rearwardly as indicated at 65' see Figure 15.
 50 60 The desk body with reference to Figures 2 and 11 to 15 inclusive includes a side wall or member 65 formed at its bottom with an inwardly extending flange 66, at its front with an inwardly extending flange 67 and at its top with an inwardly extending flange 68.
 65

The side member 65 opposes and coacts with the portion 54 of the carrier 53 to support the front wall 69, bottom wall 70 and rear wall 71 of the book box or desk body. The flanges 56, 57 and 58 coact with the flanges 66, 67 and 68 and associated with the flange 58, is a lug 72 and associated with the flange 67 is a lug 73. The lug 52 is carried by the portion 55 of the carrier 53 and the lug 73 is carried by the member 65. The front wall 70 is interposed between the lugs 72, 73 and flanges 58 and 67. The member 65 at its rear is formed with an inwardly extending flange 74 and the portion 54 of the carrier 53 is formed with an inwardly extending flange which opposes the flange 74. The inner face of the member 65, as well as the inner face of the portion 54 of the carrier 53 is formed with a pair of inwardly extending base lugs 75. The inner face of the member 65 as well as the inner face of the portion 54 of the carrier is provided with an inwardly extending lug 76'. The lugs 76' coact with the flanges 74 for maintaining the rear wall 71 in position. The lugs 75 coact with the flanges 56 and 70 for maintaining the bottom 70 in position. The lugs 72 and 73 coact with the flanges 67 and 58 for maintaining the front wall 69 in position. The rear wall 71 of the desk body or book box is disposed at a rearward inclination and the flanges 74 extend at the same inclination as the wall 71. The member 65 is connected to the portion 54 of the carrier 53 by tie bars 76, 77, 78 and 79. Loosely mounted on the tie bars 79 is a pair of hinged members consisting of a threaded shank 80 and an apertured head 81. The hinge members are in the form of eye screws and threadably engage with the study support, which as shown in Figures 11, 12 and 13, as well as Figures 1 and 2, is the top of the book box or desk body and which is indicated at 81 and is formed at one side with a rearwardly directed extension 82 which may be termed an arm rest. The front wall 69 is cut away as at 83 to provide clearances for the pivoted ends of the screw eyes 80. Cushioning members 84 are carried by the study support 81 and engage the top flanges of the member 65 and portion 54 of the carrier 53, see Figure 11. The study support or top 81 is maintained in spaced relation with respect to the top edges of the member 65 and portion 54 of the carrier 53. See Figures 11 and 13. The study support or top 81 is detachably secured in closed position with respect to the book box or desk body and the means for detachably securing the same in closed position will be presently referred to. Each of the tie bars is of the same construction and comprises an elongated shank 85 provided with a screw head 86 and with peripheral threads 87 for engaging in openings 88 formed in the portion 54 of the carrier 53. The walls 125 130

of the openings 88 are threaded and the portion 54 is provided with bosses 89 which surround the openings 88. The member 65 is provided with countersunk openings 90 for the heads 86 of the tie or connecting rods.

The locking means for the study support or top 81 consists of a pair of guide bars 91, 92 arranged in spaced relation and carried by the inner face of the member 65. Positioned between the guide bars 91, 92 is a triangular shaped locking member 93 formed with a concaved top 94. Pivottally connected to the study support or top 81, as at 95 is a latching member 96 provided with a nose 97

- 10 which engages under the lower end of the locking member 93 for maintaining the study support or top in closed position. The flange 68 is cut away as at 98 to provide a clearance for the latching member 96 when the same 15 is shifted upwardly, see dotted line position Figure 11. The flange 68 is formed with a depending cam 98 for directing the nose into the concavity 94 of the locking member 93. When the nose 97 is seated in the concavity 20 94 the top 81 will be supported in the dotted line position shown in Figure 11. To prevent the withdrawal entirely of the latching member 96 the nose 97 engages under the flange 68, see dotted line position in Figure 11.

- 25 The latching member 96 when moving to latching position passes down between the locking member 93 and the guide 92 and engages under the lower end of the locking member 93, see Figure 11. By shifting the 30 top 81 upwardly the nose 97 is caused to clear the locking member 93 and the top 81 can be moved to open position.

- Referring to Figures 16 to 21 of the drawings, the article of furniture is set up with 35 a fixed study support referred to generally by the reference character 100 and which is of angle shaped contour and consists of what may be termed a body portion 101, and an extension 102 forming an arm rest. It 40 will be stated that the study support can be of the same contour as the top 81. In the modified form, the side plate 8 is dispensed with, and the chair is set up with a chair bottom 103 and a pair of back supports 104 and which correspond in contour 45 to the back support shown in Figures 4 and 8 and which includes the lower portion 31 and the upper portion 32. It is thought unnecessary to specifically describe the back 50 supports 104 as it is the same as that shown in Figure 3. Connected to one of the back supports 104 is a bracket 105 and upon which the extension 102 is mounted and fixedly secured therewith by the hold fast devices 55 106. Fixedly secured to the chair bottom 103 is a supporting member for the body portion 101 of the study support 100, the latter may be termed a tablet arm. The supporting member is referred to generally by 60 65 the reference character 107 and includes an

upstanding arm 108 formed with a forwardly extending triangularly shaped flat enlargement 109 which is secured to the body portion 101 of the study support 100 by the hold fast devices 110. Formed integral with the 70 lower end of the arm 108 is a channel shaped extension 111 disposed at right angles with respect to the arm 108, positioned against the lower face of the chair bottom 103 and is fixedly secured therewith by hold fast 75 devices 112. The extension 111 has one of the arms 47 of the casting mounted thereon and said arm 47 is secured in position by one of the hold fast devices 112. The chair bottom 103 is rabbeted at 113 for the reception of the lower portions of the back supports 104 and said lower portions are secured to the chair bottom by the hold fast devices 113'. Hold fast devices 114 are employed for connecting the bracket 105 to one of the 80 chair supports 104. The back employed in the form shown in Figure 16 is the same as that referred to in connection with Figures 1 and 3.

It is to be understood that the term study support, applies to the stationary or hinged top of a desk or book box, or the latter, or to a tablet arm and further that the construction as hereinbefore set forth forms what may be termed a complete or full stay 90 put movable chair desk and further that the article of furniture can be used as a movable chair. By setting up the article of furniture in the manner stated the desk body or book box can be disconnected and 95 the article used as an ordinary chair. It is furthermore to be pointed out that an independent support is not provided for the desk body or book box, such as a pedestal, but that a single pedestal is employed as a 100 sole supporting means and that such pedestal is connected with the chair bottom. By setting up the construction in the manner stated the desk body or book box can be 105 removed and the chair employed. The construction and arrangement hereinbefore set forth provides means whereby the desk body or book box can be adjusted to the position desired by the occupant of the chair and that the latter can be vertically adjusted to the 110 desired points. Furthermore owing to the adjustability of the chair the study support can be elevated or lowered when desired. An article of furniture in accordance with this invention, not only includes means for 115 vertically adjusting the chair but further includes an adjustable hump for the back and an adjustable study support, which may be a tablet arm, or a desk, or any other suitable platform or table which can be coupled with the chair for the purpose of providing a study support. Therefore it is thought the many advantages of an article of furniture, in accordance with this invention and for the purpose referred to, can be readily 120 125

understood, and although the preferred embodiment of the invention is as illustrated and described, yet it is to be understood that changes in the details of construction can be had which will fall within the scope of the invention as claimed.

What I claim is:

1. An article of furniture for the purpose set forth comprising a vertically adjustable chair, a supporting pedestal for the chair and including a base providing a sole means for anchoring the pedestal in a stationary position, said chair including a seat having one side thereof free of a side rail and its other side provided with a side rail in the form of an upstanding plate, a study support arranged forwardly of the seat, and said study support and side rail having coacting means for detachably connecting the study support to the said side rail and further to provide for the bodily shifting throughout of the study support upwardly and forwardly from the seat simultaneously and downwardly and rearwardly towards the seat simultaneously to adjust the study support with respect to the seat.

2. An article of furniture for the purpose set forth comprising a standard, a seat mounted thereabove, a coupling connection between the seat and the standard and constructed for permanently maintaining the seat in a rearwardly tilted position, an upstanding back for the seat, a support for one side of the back having a forwardly extending lower end secured against one side of the seat, a side rail secured against the other side of the seat, extending thereabove and provided at its rear with a support for the other side of the back, means for securing said back to said supports, and means for securing said coupling connection between the seat and the standard to said side rail.

3. An article of furniture comprising a standard, a chair mounted thereabove and having one of its sides free of the side rail and the other of its sides provided with an upstanding side rail in the form of a plate, a study support having a rearward extension exposing said plate, said plate provided with openings and said extension provided with inclined slots registering with said openings, said plate further provided with means for guiding said study support throughout upwardly and forwardly simultaneously and downwardly and rearwardly simultaneously to adjust the study support with respect to the chair when the study support is bodily shifted respectively forwardly and rearwardly, and means extending through said openings and slots for fixedly securing the study support relative to said plate.

4. An article of furniture for the purpose set forth comprising a standard, a seat

mounted thereabove, a casting secured 65 against the lower face of the seat and having its top inclining rearwardly and downwardly from front to rear and abutting throughout thereof the lower face of the seat to permanently maintain the seat in a 70 rearwardly tilted position, said casting formed with a squared pocket disposed substantially centrally for the reception of the upper end of the standard, and a supporting pedestal for the standard.

5. An article of furniture for the purpose set forth comprising a standard, supporting means therefor, a chair consisting solely of a seat, one side rail and a back, a casting secured to and centrally of the lower face 80 of the seat and having its top rearwardly inclined for permanently maintaining the chair in a rearwardly tilted position, said casting provided centrally thereof with a squared pocket for the reception of the upper end of the standard, and a study support connected to said side rail and supported solely therefrom.

6. An article of furniture for the purpose set forth comprising a portable chair including a side rail in the form of an upstanding plate, and a study support formed of a book box having a hinged top closure and further formed with a rearward extension, said plate and extension having coacting 95 means to provide for detachably connecting the study support to the plate and further to provide for the adjusting of the study support upwardly and forwardly simultaneously and downwardly and rearwardly simultaneously with respect to the front of the chair, said coacting means constituting the sole support for said study support.

7. An article of furniture for the purpose set forth comprising a chair having one side open and its other side closed, means for supporting the chair, a study support in the form of a book box having a hinged top closure and with the body of the box formed with a rearwardly extending downwardly inclined extension, said extension and the closed side of the chair having coacting means for adjustably connecting the study support to said closed side, said coacting means constituting the sole support for the 115 study support.

8. An article of furniture for the purpose set forth comprising a chair, a supporting pedestal therefor, a suspended study support arranged forwardly of the chair and formed with a rearward extension opposing one side of the chair, the said side of the chair formed with openings and said extension formed with slots aligning with said openings, and means common to said aligning slots for adjustably connecting the study support to the chair, the said side of the chair provided with guides having said ex-

tension positioned therebetween, the said means common to said slots providing the sole support for said study support.

9. An article of furniture for the purpose set forth comprising a chair, a supporting pedestal therefor, said chair having one of its sides free of the side rail and the other of its sides provided with a side rail, a study support in the form of an open top body portion and a hinged cover therefor formed at one end of its rear with a rearwardly disposed extension arranged over said side rail, said body portion further formed at its rear, at one side thereof, with a depending inclined extension opposing said side rail, and means for connecting said inclined extension to said side rail and further to provide, when said support is bodily shifted in one direction a bodily moving of the support upwardly and forwardly simultaneously and when bodily shifted in the other direction the bodily moving of the support downwardly and rearwardly simultaneously whereby the study support can be adjusted with respect to the front of the chair.
10. An article of furniture for the purpose set forth comprising a standard, a seat mounted thereabove, an upstanding back for the seat, an upstanding support for the side of the back and having a forwardly extending lower end portion secured against one
- 5 side and the lower face of said seat, a side rail secured against the other side of the seat, extending upwardly therefrom and provided at its rear with an upstanding portion 35 to provide a support for the other side of the back, said side rail engaging the lower face of the seat, said supports positioned against the rear face and sides of the back, and means for securing the back to said supports. 40
11. An article of furniture for the purpose set forth comprising a standard, a seat mounted thereabove, an upstanding back for the seat, an upstanding support for the side of the back and having a forwardly extending lower end portion secured against one side and the lower face of said seat, a side rail secured against the other side of the seat, extending upwardly therefrom and provided at its rear with an upstanding portion 45 to provide a support for the other side of the back, said side rail engaging the lower face of the seat, said supports positioned against the rear face and sides of the back, means for securing the back to said supports, 50 and a coupling connection between the seat and standard and constructed for permanently maintaining the seat in a rearwardly tilted position.

In testimony whereof, I affix my signature 60
hereto.

WILLIAM J. BARGEN.
